UNITED STATES PATENT OFFICE.

PERRY M. SHEPARD, OF CHICAGO, ILLINOIS.

DESIGN FOR A SOAP-DISH.

46,974.

Specification for Design.

Patented Feb. 16, 1915.

Application filed November 13, 1914. Serial No. 872,021. Term of patent 7 years.

To all whom it may concern:

Be it known that I, PERRY M. SHEPARD, a citizen of the United States, residing at Chicago, in the county of Cook and State of Illinois, have invented a new, original, and ornamental Design for Soap-Dishes, of which the following is a full, clear, and exact description, reference being had to the accompanying drawing, forming a part hereof.

My invention relates to a design for a soap-dish for sinks of an attractive and pleasing appearance.

In the drawings: The drawing represents a perspective view of said soap-dish.

Referring to the drawing, it will be observed that the bowl of said soap-dish comprises a series of suitably separated longitudinally disposed wires with their ends correspondingly upturned; a series of suitably separated transverse wires with their end portions upturned in a similar manner; a rectangular edge-frame also made of wire to which the extremities of the said up-

turned end portions of said longitudinal and transverse wires are secured, and corresponding wire supports at each end of the dish. These supports each consist of a single stretch of wire bent U-shape and with the extremities formed into eyes that are looped around the end member of the edge-frame of the dish. Each leg of the bail extends down from the edge member a corresponding distance and then are bent upward and then downward again and form hooks the outer termini of which latter are connected by the stretch of wire constituting the return bend of the support.

What I claim is—

The ornamental design for a soap-dish, as shown and described.

In witness whereof, I have hereunto set my hand this 21st day of October, 1914.

PERRY M. SHEPARD.
